UNITED STATES PATENT OFFICE.

JOSEPH ZAJICEK, JR., OF NEW YORK, N. Y.

EAR AND NAIL CLEANER.

Application filed March 12, 1923. Serial No. 624,520.

To all whom it may concern:

Be it known that I, JOSEPH ZAJICEK, Jr., a citizen of the United States, residing at New York, in the county of New York and 5 State of New York, have invented certain new and useful Improvements in an Ear and Nail Cleaner, of which the following is a specification.

This invention relates to improvements in 10 toilet articles and has for its prime object to provide an instrument that can be used for various purposes.

A further object of the invention is to provide an instrument of the character 15 stated, which is formed from a single piece of metal and which can be easily carried in a vest pocket or a small hand purse.

A still further object of the invention is to provide an instrument which is simple 20 in construction, durable, efficient for the purpose intended, and one that can be manufactured and sold at a relatively low cost.

These and like objects of the invention will be better understood as the description 25 follows and as is specifically pointed out in the appended claim.

Referring to the accompanying drawing which forms a part of this specification and which clearly illustrates the construction 30 and use of my improved instrument,

Figure 1 is a perspective view of an instrument constructed in accordance with my invention.

Figure 2 is a top plan view of same.

35 Figure 3 is an edge view of same, and

Figure 4 is a horizontal section taken on line 4—4 of Figure 2.

Referring to the accompanying drawing in detail, like characters will be used to designate like parts in the different views.

In the drawing, the numeral 1 indicates as a whole my improved toilet article, which comprises a body 2 that tapers to form a sharp point or edge 3 at one end, while the 45 enlarged portion of the body is provided with shoulders 4 and has a neck 5 extending outwardly from the shoulders which is provided on each side with a roughened sur-

face 6. The extreme end of the neck portion is provided with a concaved surface 7. 50

The pointed end 3 of my instrument permits the nails to be easily and quickly cleaned, while the shoulders 4 permit the cuticle of the nails to be pushed backwardly and the roughened surfaces 6 on each side of the 55 neck 5 provide a nail file.

The extreme end of the neck portion which is rounded and provided with a concaved surface 7, permits the instrument to be used as an ear cleaner, the rounded portion preventing the same from injuring the drum of the ear in any manner and the shoulders 4 limit the inward movement of the neck 5 within the ear. 60

In view of the foregoing description of 65 my invention taken in connection with the accompanying drawing, it is thought that any further explanation as to the construction, operation, and objects of same is unnecessary. 70

While I have shown and described the preferred form of my invention, I realize that various minor changes may be resorted to, without departing from the spirit and scope of the invention as claimed, and therefore, I do not wish to limit myself to the exact details of construction shown, nor to the combination and arrangement of parts. 75

What I claim as new and desire to secure, 80 by Letters Patent is:

A device of the character described comprising a body tapering towards one end to provide a sharp, pointed edge and the opposite end forming shoulders and having a neck extending outwardly therefrom, said 85 neck being provided with a roughened surface at each side thereof, and an ear cup formed on the extreme end of the neck portion as and for the purpose specified.

In testimony whereof I have affixed my 90 signature in the presence of two witnesses.

JOSEPH ZAJICEK, JR.

Witnesses:

JOSEPH POSPISIL,
CHARLES MICHALEK.
